United States Patent Office

Des. 181,118
Patented Oct. 8, 1957

181,118

SPECTACLE FRAME FRONT

Marcel Arnant, Paris, France, assignor to Societe Industrielle de Lunetterie, Paris, France, a French company

Application April 10, 1956, Serial No. 41,001

Claims priority, application France December 21, 1955

Term of patent 7 years

(Cl. D57—1)

Fig. 1 is a front elevational view of a spectacle frame front embodying my new design;

Fig. 2 is a top plan view thereof; and

Fig. 3 is a sectional view along line 3—3 of Fig. 1. The dominant feature of my design resides in the portions shown in full lines.

I claim:

The ornamental design for a spectacle frame front, as shown and described.
